Primary Examiner — David G Muller*(74) Attorney, Agent, or Firm* — The Webb Law Firm(57) **CLAIM**

The ornamental design for a syringe flange, as shown and described.

DESCRIPTION

FIG. 1 is a topwardly-directed perspective view of a syringe flange in accordance with an embodiment of the present invention.

FIG. 2 is a front view of the syringe flange of FIG. 1.

FIG. 3 is a rear view of the syringe flange of FIG. 1.

FIG. 4 is a top view of the syringe flange of FIG. 1.

FIG. 5 is a bottom view of the syringe flange of FIG. 1. FIG. 6 is a right-side view of the syringe flange of FIG. 1; and,

FIG. 7 is a left-side view of the syringe flange of FIG. 1. The broken line showing of parts of the drawings is included for the purpose of illustrating use and environment and forms no part of the claimed design.
